UNITED STATES PATENT OFFICE

118,763

DESIGN FOR A JEWELRY COMPONENT

Edward A. Weiss, Attleboro, Mass., assignor to Guyot Brothers Company, Incorporated, a corporation of Massachusetts

Application November 24, 1939, Serial No. 88,472

Term of patent 3½ years

To all whom it may concern:

Be it known that I, Edward A. Weiss, a citizen of the United States of America, residing at Attleboro, county of Bristol, State of Massachusetts, have invented a new, original, and ornamental Design for a Jewelry Component, of which the following is a specification, reference being had to the accompanying drawing, forming a part thereof.

Fig. 1 is a top plan view of a jewelry component showing my new design;

Fig. 2 is a side elevation; and

Fig. 3 is a section on line 3—3 of Figure 1.

I claim:

The ornamental design for a jewelry component, substantially as shown.

EDWARD A. WEISS.
